UNITED STATES PATENT OFFICE.

NORMAN G. ELLIS, OF WASHINGTON, DISTRICT OF COLUMBIA.

VARIABLE-SPACING MECHANISM FOR TYPE-WRITERS.

No. 828,201.

Specification of Letters Patent.

Patented Aug. 7, 1906.

Application filed October 5, 1905. Serial No. 281,556.

To all whom it may concern:

Be it known that I, NORMAN G. ELLIS, a citizen of the United States, residing at Washington, District of Columbia, have invented 5 certain new and useful Improvements in Variable-Spacing Mechanism for Type-Writers, of which the following is a specification.

My invention relates to type-writing machines, and particularly to means whereby 10 variable spacing may be obtained to a greater extent than is now possible in the present state of the art.

In carrying out my invention I employ a platen having a plurality of circumferential 15 rows of teeth or ratchet-wheels which in respect to each other will produce a differential effect as regards spacing, the said platen being supported to have longitudinal movement to bring either of the said ratchet-wheels into 20 line with the devices for turning and controlling the platen, means being provided for holding the platen in any position to which it may be adjusted longitudinally, while allowing it freedom of turning movement under 25 the action of its operating devices.

The invention consists in the features and combination and arrangement of parts hereinafter described, and particularly pointed out in the claims.

30 In the accompanying drawings, Figure 1 is a plan view of so much of a type-writer carriage as is necessary for a clear understanding of my invention, said carriage having in place therein my improved form of platen 35 and devices associated therewith. Fig. 2 is a detail view of the clip or detent for holding the platen in any one of its longitudinal positions. Fig. 3 is a detail end view of a type-writer carriage of the well-known Remington form having my improvement attached thereto, the differential spacing-ratchets in 40 this form of my invention being of the same diameter.

In the drawings, 1 indicates the platen, 45 and 2 indicates a conventional form of type-writer carriage. The shaft of the platen is suitably supported in the carriage-frame, so that it, together with the platen, may have an adjustment in the direction of its axis, or, in 50 other words, longitudinally of the said frame. At one end the platen is provided with a series of rows of teeth or ratchet-wheels having in respect to each other teeth of different distances apart, or the teeth may all be of substantially the same size but on wheels of different diameters, or, again, the teeth may be

of different size and on wheels of different diameters, the purpose being to secure different degrees of angular movement of the platen according to which row of teeth is in line with the operating-pawl. In any case, whether the teeth be of different sizes on wheels of the same or different diameters or of the same size but on wheels of different diameters, the teeth in respect to the several wheels may 60 be said to be differently disposed. These ratchet-wheels are indicated generally at 3, and individually they are designed to coöperate with an operating-pawl 4 of substantially the ordinary form pivotally connected with 70 the hand-lever 7. The ratchet-wheels may also have associated therewith the ordinary form of detent, together with means well known in the art whereby the said detent may be lifted from the ratchet-teeth in order 75 to entirely free the platen from restraint. The pawl 4 may be of that character which is normally disengaged from the ratchet-teeth.

In order to hold the platen in any position to which it may be adjusted longitudinally 80 for bringing any one of the ratchet-wheels into line with the pawl, I employ a clip or detent 6, which I preferably pivot to the carriage-frame and allow it to engage the appropriate one of a series of grooves 5 in the platen- 85 shaft, of which grooves there is one for each of the ratchet-wheels. When a different circumferential spacing movement of the platen is desired from that for which the machine is set, it is simply necessary to lift the detent 6 90 from engagement with the groove in the shaft and then to shift the platen longitudinally until the appropriate ratchet-wheel is in line 95 therewith. In this manner the platen will be held against longitudinal displacement while permitted rotary movement under the action of the operating-pawl.

In order to hold the clip or detent 6 in 100 place, a lock or holding-piece 8 may be employed pivoted to the carriage-frame at 9.

It will be understood that the operating and controlling mechanism for the platen may be in all substantial respects similar to that now 105 employed and that these parts will need no adjustment out of the vertical plane in which they operate in order to carry out the purposes of the invention.

Further, it will be understood that my invention can be used either with or without the devices now employed for securing vari-

able line-spacing, and when used in connection with said devices the employment of the plurality of ratchets will multiply according to the number used the number of different line-spacings which it is possible to secure with the ordinary means.

Where I employ herein the term "ratchet-wheels," I do not necessarily mean a set of independent wheels, as the teeth may be formed 10 on one body, if desired.

I claim as my invention—

1. In combination in a type-writer, a platen-frame, a platen, a plurality of ratchet-wheels fixed thereto and having in respect to each other differently-disposed teeth for producing different degrees of rotary spacing movements, operating means to engage said ratchets, and means for setting the platen in different positions longitudinally to aline the 20 ratchets severally with the operating means, substantially as described.
2. In combination in a type-writer, a platen-frame, a platen and platen-shaft, a plurality of ratchet-wheels connected to the 25 platen and having in respect to each other different disposed teeth for producing different degrees of rotary spacing movements, operating means to engage said ratchets, said platen-shaft having longitudinal shifting 30 movement in the same bearings in which it

rotates to bring the ratchets severally into line with the operating means and detent means for holding the shaft with the platen in different positions longitudinally, substantially as described.

3. In combination in a type-writer, a platen-frame, a platen, a shaft carrying the platen, shiftable longitudinally in its bearings in the frame and having a plurality of circumferential shoulders or grooves, a plurality of ratchets connected to the platen and having in respect to each other differently-disposed teeth, means for operating the platen by engaging the ratchets and means engaging the grooves or shoulders for holding the platen in 40 its different longitudinal positions, substantially as described.

4. In combination in a machine of the class described, a rotary platen, means for giving the platen different line-spacing movements 45 and means for setting the platen in different positions longitudinally for the various line-spacing movements, substantially as described.

In testimony whereof I affix my signature 55 in presence of two witnesses.

NORMAN G. ELLIS.
